EDWARD W. MUNSON AND WILLIAM P. THOMAS, OF WATERBURY, CONNECTICUT.

Letters Patent No. 82,863, dated October 6, 1868.

IMPROVEMENT IN WINDOW-SPRINGS.

The Schedule referred to in these Letters Patent and making part of the same.

TO ALL WHOM IT MAY CONCERN:

Be it known that we, EDWARD W. MUNSON and WILLIAM P. THOMAS, of Waterbury, in the county of New Haven, and State of Connecticut, have invented a new Improvement in Window-Spring; and we do hereby declare the following, when taken in connection with the accompanying drawings, and the letters of reference marked thereon, to be a full, clear, and exact description of the same, and which said drawings constitute part of this specification, and represent, in

Figure 1, a perspective view of the window-spring detached.

Figure 2, the rose or plate upon which the knob of the spring rests; and in

Figure 3, a side view of the window-jamb with the spring placed therein.

This invention relates to an improvement in the article known to the trade as window-springs, such as are used for holding a window at any required point; and the invention consists in the arrangement of a bolt within a case, and projecting from the said case, so as to pass into a notch cut in the face-side of the sash, and the said bolt combined with a rod, which extends through the jamb, the said rod provided with a shoulder, and passing through a rose or plate, and so that when, by means of the said rod, the spring is drawn out, the shoulder on the rod may be dropped on to the plate, so as to hold the bolt withdrawn from the sash in order to enable the person to apply both hands to the raising or lowering of the window, as the case may be.

To enable others to construct and use our improvement, we will proceed to describe the same as illustrated in the accompanying drawings.

A is the case, of any suitable metal, provided with ears B, or other suitable means, for securing to the window-frame, and into the said case is fitted the bolt C, so as to move freely therein and project therefrom, as in fig. 1.

From the said bolt a rod, D, extends out, of sufficient length to project through the jamb, for the attachment of a knob, E, or other convenient device, for operating.

The said rod is constructed with a shoulder, α , as seen in fig. 1; and upon the face of the jamb, beneath the said knob, a plate, F, is placed, the said plate being shown detached in fig. 2, the hole G, through the plate, corresponding to the size of the rod at the neck of the knob; and at the edge of the said hole G, we form a notch, d , corresponding so the size of the rod at the shoulder α ; so that when the rod is dropped into the notch d , the shoulder will rest upon and bear against the plate.

Within the case we arrange a spiral or other suitable spring, as seen in fig. 3, the tendency of which is to force the bolt outward.

Placed in the jamb, as seen in fig. 3, a notch is cut into the sash to receive the bolt C, and by the said notch the sash is firmly held in that position, the notches being arranged at such points as it is desired to sustain the sash.

To move the sash thus fastened, take hold of the knob E, and draw out the knob and bolt, as denoted in red, fig. 3, drop the rod into the notch d in the plate F, so that the shoulder α will bear against the plate, and the bolt will be held withdrawn from the sash, so that both hands may be applied to the raising and lowering of the sash. When the sash is raised, then release the rod from the notch d , and the spring will return the bolt into another notch in the sash whenever the sash presents such a notch to the bolt.

This spring, it will be seen, is equally adapted to an upper and lower sash.

Having thus fully described our invention, what we claim as new and useful, and desire to secure by Letters Patent, is—

The case A, within which is arranged the bolt C, and combined with the rod D, constructed with a shoulder, α , and with a rose, F, the whole constructed and arranged so as to operate in the manner substantially as specified.

EDWARD W. MUNSON.
WILLIAM P. THOMAS.
